UNITED STATES PATENT OFFICE.

HERMAN E. SCHULTZ, JR., OF ST. LOUIS, MISSOURI.

DESIGN FOR A FABRIC.

40,482.

Specification for Design.

Patented Feb. 1, 1910.

Application filed October 20, 1909. Serial No. 523,729. Term of patent 7 years.

To all whom it may concern:

Be it known that I, HERMAN E. SCHULTZ, Jr., a citizen of the United States, residing at St. Louis, in the State of Missouri, have invented a new, original, and ornamental Design for a Fabric, of which the following is a specification, reference being had to the accompanying drawing, forming part thereof.

The figure is a plan view of a fabric, showing my new design.

The same, as depicted, comprises a stripe distinguished by three (3) comparatively heavy parallel lines, each stripe inclosing a

peculiar broken lacing effecting alternate diamond-shaped and triangular areas, and is particularly, though not necessarily, adapted for the decoration of canvas, more especially in the use of such material for the construction of awnings, tents, tarpaulins, wagon and "advertising" umbrellas.

I claim—

The ornamental design for a fabric, as described and illustrated.

HERMAN E. SCHULTZ, JR.
